Herbert E. Smith

Attorney

UNITED STATES PATENT OFFICE.

FRANCIS L. KIMBALL, OF SPOKANE, WASHINGTON, ASSIGNOR OF ONE-HALF TO
HOMER PRATHER, OF SPOKANE, WASHINGTON.

CIGARETTE HOLDER.

Application filed February 15, 1924. Serial No. 692,997.

To all whom it may concern:

Be it known that I, FRANCIS L. KIMBALL, a citizen of the United States, residing at Spokane, in Spokane County and State of Washington, have invented certain new and useful Improvements in Cigarette Holders, of which the following is a specification.

My present invention relates to improvements in cigarette holders with which is combined and embodied an ash retainer or receptacle that also performs the functions of a shield against wind for the lighted cigarette when a smoke is being enjoyed in the open air.

15 By the utilization of my invention a novel and attractive device for smokers' use is provided which insures sanitation for the smoker, affords cleanliness to the dwelling by preventing the dropping of ashes as the 20 cigarette is being consumed, adds to the pleasure of the smoker when the cigarette is being enjoyed in the open air, and assures a convenient and reliable means for holding the cigarette when in use.

25 With these ends in view the invention consists in certain novel parts and combinations and arrangements of features of construction as will hereinafter be more fully set forth and claimed.

30 In the accompanying drawings I have illustrated one complete example of the physical embodiment of my invention wherein the parts are combined and arranged in accordance with the best mode I have thus far 35 devised for the practical application of the principles of my invention.

Figure 1 is a view in side elevation of the device of my invention.

Figure 2 is a central, longitudinal sectional view of the device of Figure 1 on an enlarged scale.

Figure 3 is a still further enlarged, detail sectional view of the device, partly broken away, illustrating the clamping or retaining 45 means of the holder.

Figure 4 is a perspective view of the combined cigarette clamp and attaching plug within the holder.

In carrying out my invention I utilize the 50 usual form of mouth piece 1 of suitable material and preferably fashioned with the customary end bead 2. At the end opposite to the bead the mouth piece is enlarged and

fashioned with an exteriorly tapered head 3 and interiorly threaded socket 4.

The cigarette C is retained at one end in the cylindrical metallic head 5, the latter being fashioned with a number of fingers 6 to clasp the end of the cigarette. These fingers are preferably of resilient metal to 60 permit the cigarette end being inserted between them and into the open head 5, or the resilient fingers may be slipped over the end of the cigarette if preferred.

Each of the fingers is provided with an 65 outward bend 7 which bends form an annular series of friction faces extending transversely of the fingers and projected beyond the periphery of the hollow metallic head 5 of the retainer. The metallic head is secured 70 in the mouth piece 1 by means of the hollow screw plug 8 fashioned integral with the metallic head and of the proper diameter to fit neatly into the socket 4 of the mouth piece.

75 The mouth piece and retaining head with its fingers thus form a holder for the cigarette C as indicated, and in combination with these parts I preferably utilize a tubular shield or cylinder 9 of suitable material for 80 enclosing the cigarette and performing the functions of an ash receptacle. The tubular cover or shield is provided with perforations 10 extending transversely through its walls and occupying substantially the entire area of the shield, and at one of its open ends is fashioned with beveled walls as 11 to form a tapered socket or seat for frictional engagement with the tapered head 3 of the mouth piece, thus providing a substantial connection or joint between these 85 members of the device.

90 The shield is of sufficient and ample size to completely enclose the entire length of the cigarette C, and an annular exterior 95 groove is formed in the shield, near its outer end, to provide an interior annular rib or bead 12 which performs the functions of a support for the free end of the cigarette. After the cigarette has been properly positioned in the retaining head and fingers of the holder, the shield is slipped over the free end of the cigarette and the socket of the shield frictionally engaged with the tapered head of the mouth piece. In the 100 absence of the cover or shield, the fingers 6

grasp the cigarette with sufficient firmness to retain the cigarette therein. When the cover is slid into place on the mouth piece the interior surface of the shield frictionally contacts with the protuberances 7 of the fingers, slightly compressing the fingers on the cigarette to clamp them and more firmly retain the end of the cigarette in the fingers.

The annular bead 12 which surrounds the free end of the cigarette exerts sufficient friction thereon to support the cigarette but does not restrict it sufficiently to prevent a draft of smoke therethrough. Nor do the compressed fingers exert pressure on the cigarette such as would interfere with the passage of smoke to the mouth piece.

In addition to the ventilation of the interior of the shield by the presence of the perforations therein I place a reticulated screen or disk 13 in the outer end of the cylindrical shield, which is secured therein by means of a screw ring 14 threaded into the end of the shield.

Transparent panels, of glass or other material, as 15 are inset in the walls of the shield and extend longitudinally thereof by means of which the cigarette is visible for inspection, and the progress of consumption of the cigarette may be noted, especially in the dark. While the perforations in the shield are of sufficient size to permit ventilation of the interior thereof they are not large enough to permit spilling of the ashes. The ashes are emptied by first removing the shield and then they may be poured therefrom, and the butt end of the cigarette withdrawn from the holder.

Having thus fully described my invention, what I claim as new and desire to secure by Letters Patent is—

1. The combination with a mouth piece having a socket, of a holder comprising a hollow head and hollow screw plug, resilient fingers on said head having an annular series of protuberances, an enclosing shield having means for frictionally engaging the mouth piece, and said shield adapted to frictionally engage said protuberances, for the purpose described.

2. The combination with a mouth piece having a tapered end and threaded socket therein, of a hollow retaining head having a hollow screw plug in said socket, resilient fingers on said head and friction members on said fingers, an enclosing, perforated shield having a tapered end seat to frictionally engage said tapered end, and said shield adapted to engage said friction members for the purpose described.

3. The combination with a mouth piece having a tapered end and threaded socket therein, of a hollow retaining head having a hollow screw plug in said socket, resilient fingers on said head having protuberances, an enclosing perforated shield having a tapered end seat to fit said tapered end and adapted to frictionally engage said protuberances, a screen and securing means therefor in the free end of the shield, and said shield having an interior annular rib, for the purpose described.

In testimony whereof I affix my signature.

FRANCIS L. KIMBALL.
